UNITED STATES PATENT OFFICE.

WALTER BOND AND JESSE BAXENDALE, OF BOLTON, ENGLAND.

PICKING-STICK FOR UNDERPICK-LOOMS.

No. 920,528.

Specification of Letters Patent.

Patented May 4, 1909.

Application filed November 17, 1908. Serial No. 463,036.

To all whom it may concern:

Be it known that we, WALTER BOND and JESSE BAXENDALE, both subjects of the King of Great Britain and Ireland, and both 5 residents of Bolton, in the county of Lancaster, England, have invented new and useful Improvements in Picking-Sticks for Underpick-Looms, of which the following is a specification.

10 These improvements relate to the picking sticks or picking shafts of underpick looms, and their object is to so construct such sticks or shafts as to increase their durability, to strengthen them so as to avoid the cost of 15 frequent renewals, and to enable the renewal of the tip to be effected at a very small cost. Such sticks as at present commonly made and used consist of a properly shaped piece of wood, the lower end of which is carried in 20 and secured to a rocking socket which is suitably operated to actuate the stick and the upper end of which enters into the shuttle box to impart motion to the picker and the shuttle. Such sticks frequently break at or 25 near a third of their length downward from the tip or at about where they enter their shuttle boxes. To reduce the disadvantages following on such breakages it has before now been proposed to mount the ordinary wooden picker stick in a metal sheath 30 along which it could be adjusted so that as part of the stick was broken off the remainder could be moved along the sheath to enter the shuttle box and act on the picker. The 35 disadvantage of such an arrangement is the necessity of properly shaping the broken end before it can be engaged with the picker.

In carrying our invention into effect we make breakages impossible or reduce the risk 40 of breakages to a minimum by dispensing with the wooden picking stick, and replacing it by a suitable metallic one, of a length insufficient to reach into the shuttle-box, and provided with a wooden or non-metallic tip 45 or end to enter the shuttle-box. The metallic picker stick has a length which extends upward past the point where breakage heretofore usually occurred as above explained, and may be secured in a rocking socket in the 50 same manner that a wooden one is at present or it may be otherwise suitably mounted and operated. The wooden or non-metallic end or tip of the stick may be composed of the same wood as is at present commonly used in 55 wooden picking sticks, and is removably attached to the metallic part so as to be readily

removed therefrom when worn and be replaced by a new tip.

A preferred form of our improved picker stick is illustrated in the accompanying drawings, in which—

Figure 1 is an elevation of a picking stick formed according to this invention. Fig. 2 shows a cross section of the same stick along the line X—Y Fig. 1. Fig. 3 shows the same stick in elevation at right angles to the view shown in Fig. 1.

Referring to the drawings, the stick is composed of or formed with a metallic main part A which is channel shaped in cross section. This part may conveniently be stamped out of sheet metal. To its upper end is attached the removable wooden tip B which enters the shuttle box and operates the picker in the usual manner. This tip may be secured to the part A by screws or equivalent fastening devices as desired. In a preferred construction and as illustrated the part A is filled with a wooden filling C, the upper end of which is formed with a tapered 70 groove or recess C¹ extending transversely through it. The inner end of the tip is formed with a corresponding tapered part B¹ which enters into and engages with the recess in the filling C. When the parts are 75 assembled and the tip B is in place the whole may be firmly held together by placing a sheet metal cap D in place over the upper end of the part A and clamping or holding all the different parts together by screws and 80 nuts E, E¹. The lower end of the composite stick has screw holes F by which it may be secured to the rocking socket in the manner usual with picking sticks.

As will be seen, the recess C¹ in the filling, 95 is of a general or average cross sectional area less than a similar area of the interior of the channel bar, and that the insertible portion of the tip substantially fits said recess. By this construction the insertible portion is 100 practically incorporated with the filling, the whole producing a structure in which the tip is braced against strains by the filling as well as by the end walls of the channel bar, owing to the fact that the filling is of a width to 105 extend from one wall of the channel bar to the other. In addition, the provision that the tip has a cross sectional area of its exposed surface adjacent the juncture thereof with the insertible portion greater than that 110 of a similar area of the insertible portion, thereby forming shoulders which rest against

the ends of the filling and of the channel bar provides an additional bracing against a rocking movement of the tip.

It is evident from the foregoing description and illustrations that the main part A of the improved picker is practically unbreakable and that if the tip B breaks or wears out it can be simply and easily replaced at a minimum cost.

10 We claim:—

1. A picking stick for looms comprising a rigid metallic channel bar having a filling, said filling having a recess extending longitudinally of the stick and of a general cross sectional area less than a similar area of the interior of the channel bar, a tip seatable within said recess, said tip having a cross sectional area of its exposed surface adjacent the juncture thereof with the insertible portion greater than that of a similar area of the insertible portion, the insertible portion substantially fitting said recess, and removable means for retaining the tip in its inserted position.
- 20 2. A picking stick for looms comprising a

rigid metallic channel bar having a filling, said filling having a recess extending longitudinally of the stick and of a general cross sectional area less than a similar area of the interior of the channel bar, a tip seatable within said recess, said tip having a cross sectional area of its exposed surface adjacent the juncture thereof with the insertible portion greater than that of a similar area of the insertible portion, the insertible portion substantially fitting said recess, and removable means for retaining the tip in its inserted position, said means including a clip adapted to embrace the edges of the channel bar and extend over the filling and the 40 insertible portion.

In witness whereof we have hereunto set our hands in the presence of two subscribing witnesses.

WALTER BOND.
JESSE BAXENDALE.
